[57] CLAIM

The ornamental design for a spinner for bike hub, as shown and described.

DESCRIPTION

FIG. 1 is a perspective view of a spinner for bike hub showing my new design;

FIG. 2 is a side elevational view thereof, the opposite side being a mirror image of the side shown herein;

FIG. 3 is an end elevational view thereof; and

FIG. 4 is a perspective view of a spinner for bike hub showing a second embodiment of my new design, the differences being in the enlarged central hub adapter and the reduced length of the spokemembers.
